(57) **CLAIM**

The ornamental design for an animal feeding and drinking trough, as shown and described.

DESCRIPTION

FIG. 1 is a front, top and right-side perspective view of an animal feeding and drinking trough showing my new design; FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom and left-side perspective view thereof;

FIG. 9 is an enlarged view, of circled portion 9, of FIG. 1, thereof; and,

FIG. 10 is an enlarged view, of circled portion 10, of FIG. 1, thereof.

The broken lines throughout the drawing figures depict portions of the animal feeding and drinking trough that form no part of the claimed design.

The dot-dash broken lines depict the boundaries of the FIGS. 1, 9 and 10 enlargement that forms no part of the claimed design.
